Inventor,
Henry Wright.

UNITED STATES PATENT OFFICE.

H. WIGHT, OF CAMBRIDGE, MASSACHUSETTS, ASSIGNOR TO WM. C. MCCLALLAN, OF SPRINGFIELD, MASSACHUSETTS.

WOODEN-SOLED SHOE.

Specification of Letters Patent No. 27,414, dated March 6, 1860.

To all whom it may concern:

Be it known that I, HENRY WIGHT, of Cambridge, county of Middlesex, and State of Massachusetts, have invented new and useful Improvements in the Manufacture of 5 Boots and Shoes Having Wood Soles; and I do hereby declare that I believe the following to be a full and exact description thereof, reference being had to the accompanying 10 drawings and to the letters of reference marked thereon.

The nature of the first part of my improvement in the manufacture of boots and shoes, having wood soles, consists in the use 15 of two soles, instead of one only, which has been the method of constructing them heretofore, the upper to which, has been secured thereto (by means of a rabbet formed on the edge with nails) between which the 20 upper is secured by any well known proper fastenings; and the nature of the second part of my improvement consists, in making a groove, or slit, in the edge of the sole, and securing the upper therein by any of the 25 well known proper fastenings, in such cases as where the boot or shoe is formed with one sole. By constructing the wooden sole in two parts, or having two soles, a great advantage is gained—the finest and most 30 delicate leather, as well as the heaviest in use, may be lasted and formed into a shoe or boot of a neat and elegant style with the same convenience as it could be, were leather soles used, and by rabbeting the upper part 35 of the edge, and cutting a groove in the edge of the sole (one sole) the upper leather may be lasted in the same way, and the welt edge secured into the said groove, thus in this way also producing a neat and elegant style, 40 as if formed, or made of leather.

To explain my invention fully and clearly, I will refer to my drawings, in which—

Figure 1, shows a gaiter boot, or shoe, as completed. Fig. 2, *a*, *b*, shows an edge view 45 of the two soles before the upper part is put on, or the two soles fastened together. Fig. 3, *a*, *b*, shows the form or shape of the two soles on the upper side. Fig. 4, is a cross section of the boot completed in the line, *f*, 50 showing one of the methods in which the leather is fastened to the upper sole, and also the way the two soles are fastened together. Fig. 5, shows two ways for fastening the leather to the upper sole, and fastening 55 the two soles together. Fig. 6, shows

how the leather and the soles are put together, when they are fastened by cement or any other of the well known proper fastenings. Fig. 6, also shows a groove *k*, cut in the edge of the sole, (*a*, and *b*, being one sole,) and the upper *d*, secured therein by any of the well known fastenings, as cement, nails, pegs, screws, &c., and it will be clearly seen that the upper may be secured thoroughly in this way without exposing to view 65 any of its fastenings.

a is the under sole, *b* is the upper sole, (or *a*, and *b*, are one sole), *c* the screws by which the two soles are fastened together.

d is the upper leather, *e* the nails which 70 fasten the leather to the upper sole, or as shown in Fig. 5 to both soles.

In constructing boots and shoes, on my improved plan I propose to have the upper parts closed and prepared in a similar manner to what they should be if leather soles were to be put on, then I put them onto the last, and attach the leather to the inner sole, by driving nails, or pegs, *e*, through the leather, and into the edge of the sole *b*, as 75 shown at Figs. 1, and 4, or as shown at *h*, Fig. 5, and then I fasten the outer sole to the inner with screws (or other proper, suitable fastenings) as shown in Fig. 4, or with 80 nails or pegs, or I fasten them with cement, 85 or I have the leather bent around the edge, and a little way on the under side of the inner sole, and then the outer sole put on, and the same nail or peg, (*e*), which fastens the 90 two soles together, also passes through the leather, and secures it between the two soles as shown at (*i*) Fig. 4, also the leather may be fastened to the soles as shown in Fig. 6, 95 by having it bent around the edge of the inner sole, and a little way under it, and fastened to it with cement, or its equivalent, and then the outer sole fastened with cement, or other substantial equivalents, also when I use only one sole as in Fig. 6, (*a*, *b*,) being considered as one sole,) its edge being 100 grooved and rabbeted and the upper being secured therein by the use of proper fastenings.

It will readily be seen that in using wood as a material for boot and shoe soles, they 105 will be brought almost if not entirely on a par with leather, in point of utility. The shoe can be twisted with equal facility. The leather can be secured to the sole with equal firmness, without being subject to ground 110

wear, and, in some of the ways of fastening the leather to the sole, the shoe can be made with equal neatness, and good taste, with those having leather soles. Besides, if 5 this material can be substituted for leather to any considerable extent, it will supply a great want which has been felt for several years past. The demand for leather has grown faster than the supply.

10 What I claim is—
The new manufacture of boot or shoe de-

scribed, viz., a boot or shoe with a wooden sole having the tops or upper fastened to the sole in a proper manner by pegs, nails or screws, passing through a portion of the 15 wood of the sole and through the upper or edge of the top and into the wood of the sole again substantially as set forth.

HENRY WIGHT.
